UNITED STATES PATENT OFFICE.

MOSES M. MARCUSE, OF NEW YORK, N. Y.

DESIGN FOR A CASING FOR DRIP-DISINFECTORS.

41,219.

Specification for Design.

Patented Mar. 7, 1911.

Application filed December 18, 1908. Serial No. 468,233. Term of patent 14 years.

To all whom it may concern:

Be it known that I, MOSES M. MARCUSE, a citizen of the United States, residing in the borough of Manhattan, city, county, and State of New York, have invented a new, original, and ornamental Design for a Casing for Drip-Disinfectors, of which the following is a specification, reference being had to the accompanying drawing.

The invention has reference to ornamental external casings generally attached to the wall and intended to contain mechanical means for delivering disinfecting fluid drop by drop.

This casing is shown at Figure 1 of the drawing in front view and in Fig. 2 a top view is shown.

The design consists in the conformation of the casing shown combined with vertical fluting shown at A and the perforations shown at B. As shown the casing is rounded in front and extends on each side back to a flat back shown at C.

What I claim is—

The ornamental design for a casing for drip disinfectors, substantially as shown and described.

MOSES M. MARCUSE.
